UNITED STATES PATENT OFFICE.

HERBERT H. HUGHES, OF ST. LOUIS, MISSOURI.

DOLLY-BAR.

1,156,142.

Specification of Letters Patent. Patented Oct. 12, 1915.

Application filed August 21, 1913. Serial No. 785,890.

To all whom it may concern:

Be it known that I, HERBERT H. HUGHES, a citizen of the United States, residing at St. Louis, in the State of Missouri, have invented 5 a new and useful Dolly-Bar, of which the following is a specification.

My invention relates to the construction of appliances used in heading rivets in fabricating and erecting structural iron work, 10 and particularly relates to the class of tools known in the art as "dolly-bars" which are employed to engage with one head of rivets to hold the rivets in position within the holes in which they are placed while a head is 15 being formed on the opposite end of the rivets.

One object of my invention is to provide a "dolly-bar" having improved means whereby the bar is more readily held in engagement with the head on one end of the rivets by the operative while the opposite end is being upset to form a head thereon.

Another object of the invention is to provide a "dolly-bar" having novel means whereby the jar on the operator's arm during the riveting operations, is greatly lessened and to a large extent is overcome.

A further object of the invention is to provide a "dolly-bar" having a detachable 30 rivet snap for engaging with the heads of the rivets being driven and having novel means for holding the rivet snap in position on the "dolly-bar."

Still further objects of my invention will 35 become apparent as the invention is more fully described hereinafter.

Referring to the drawings forming part of this specification, Figure 1 is a longitudinal section showing a "dolly-bar" as constructed and arranged in accordance with 40 my invention. Fig. 2 is a sectional end view on the line II—II of Figs. 1 or 4. Fig. 3 is a similar transverse section on the line III—III of Figs. 1 and 4 showing the 45 means employed for yieldingly holding the rivet snap in position on the end of the "dolly-bar." Fig. 4 is a section similar to that of Fig. 1 showing a modified form of bar also constructed in accordance with my 50 invention.

In the accompanying drawings the hollow shell or casing of my improved "dolly-bar," which may be conveniently formed of pieces of wrought iron pipe, as shown in Fig. 1, is 55 formed in two sections, the end of the larger section 2 being swaged and shrunken on one

end of the smaller section 3 of the shell so as to fasten the sections together and form in effect a substantially hollow one piece casing. The rear end of the casing is screw-threaded and has a cap 5 removably secured thereon, this cap being provided with internal threads engaging the threads on the end of the casing or shell 3.

Within the hollow casing is a coil spring 6, one end of which engages with the cap 5 and also positioned within the smaller section 3 of the shell or casing is a plunger 7 having a reduced portion 8 which is within the coils of the spring 6, the end of the spring engaging with the shoulder 9 formed at the junction of the reduced portion 8 with the main portion of this plunger 7. Also positioned within the casing is a second plunger 10 having a reduced portion 11 extending into the small section 3 of the casing and having a recessed outer end which projects beyond the end of the section 2 of the casing in which the plunger 10 is secured so as to be lengthwise movable. A second coil 80 spring 12 is inserted within the casing 2 one end of this spring engaging with the shoulder 13 formed by the end of the smaller section 3 of the casing, and the other end of the spring engaging with the shoulder 14 85 formed on the plunger 10 at the intersection of the reduced portion 11 with the larger or body portion 10 of the plunger. The plunger 10 has a transverse opening therethrough in which a pin 15 is inserted and 90 the ends of this pin project into the slots 16, 16 in the wall of the casing 2 so as to limit the endwise movement of the plunger within the "dolly-bar" casing.

A sleeve 17 having inwardly curving ends 95 18, 18 is provided to slip over the outside of the casing 2, the curved ends 18 of the sleeve springing into annular grooves 19, 19 formed in the outer surface of the sleeve 2, in this way providing a guard which holds the pin 15 in position during the operation of the "dolly-bar." The guard sleeve 17 is adapted to slip lengthwise when pulled with sufficient force so as to uncover the slots 16 when it is desired to remove the pin 15 from 100 its position within the plunger 10 and casing 2.

Positioned within the recess 20 in the outer end of the plunger 10 is a rivet snap 21 having a recess 22 in the outer end thereof made to a standard size to fit a given size rivet head. The rivet snap 21 comprises a 110

head portion having the recess 22 and a reduced portion 23 forming a shank which projects into the recess 20 in the end of the plunger 10. An annular groove 25 in the 5 end of the shank 23 of the rivet snap registers with a similar annular groove 26 within the wall of the recess 20 of the plunger 10 and a split spring ring 27 is inserted within the recess in the snap so that when the shank 10 23 of the rivet snap is positioned within the recess in the plunger 10 the spring ring 27 will expand therein and hold the rivet snap in position when the "dolly-bar" is in use but still permit the removal of the snap by 15 a jerk or pull when desired.

The slots 16 in the side of the "dolly-bar" casing are positioned and are of such length that when the operator exerts the usual amount of endwise pressure on the "dolly-bar" casing found to be necessary in holding the rivet snap 21 in engagement with a rivet head, the pin 15 in the slots 16 will be positioned at a point about the center of the length of the slots so as to be movable toward either end of the slots during the riveting operations.

The abutting ends of the plungers 7 and 10 and the socket end of the plunger are case-hardened so as to prevent battering or 30 upsetting thereof in the operation of the "dolly-bar".

In the modified construction shown in Fig. 4 the "dolly-bar" is provided with an intermediate plunger 4 having a reduced 35 portion 28 on which a third spring 29 is positioned, one end of the spring engaging with the shoulder 30 formed by the junction of the reduced portion with the body portion of this plunger. The casing of the 40 "dolly-bar" of Fig. 4 includes a middle section 31 in addition to the end sections 2 and 3. The sections of the casing are secured together in the same manner as in Fig. 1 and in other respects the construction of the 45 "dolly-bar" is the same as that shown in Figs. 1, 2 and 3. In this construction the ends of the plungers 7 and 10 engage with the ends of the third plunger 4 instead of with each other.

50 It will be seen that a plurality of plungers, each engaging with a spring, are employed in my improved "dolly-bar", and it will also be readily seen that its springs are separately supported so that each plunger 55 and its spring operates independently of the other and, while but two plungers are shown employed, a larger number of such plungers may be used when found desirable or necessary.

60 In the operation of my improved apparatus the parts are assembled in the manner shown, and a rivet snap of the desired size is inserted in its socket in the "dolly-bar". When a rivet is to be upset, the rivet is 65 placed in position within the hole it is to

fill in the usual manner. The "bucker-up" or operator then holds the "dolly-bar" with the rivet snap 21 in engagement with the rivet head and exerts a pressure on the "dolly-bar" so as to hold the rivet snap 21 tightly in engagement with the rivet head. The pressure exerted by the "bucker-up" will compress the springs 6 and 12 on the plungers 7 and 10, this operation moving the pin 15 rearwardly in the slots 16 in the "dolly-bar" casing. The operator readily determines the amount of pressure necessary to maintain on the "dolly-bar" during the riveting operations. The opposite end of the rivet is then engaged by a pneumatic riveter to form a head thereon, or a hammer is employed to form the head, in the usual manner.

The shock of the blows transmitted to the snap through the rivet from the rivet hammer will be absorbed by the springs, and in this way the jar usually transmitted to the arms of the "bucker-up" is very much lessened, so as to materially reduce the exertion necessary in driving rivets and greatly increase the capacity of the workmen and enable a much larger number of rivets being driven by the workmen.

As the shock of riveting is taken up by the springs, the great weight heretofore necessary in such "dolly-bars" can be materially reduced, and in this way lessen the manual labor necessary in handling the "dolly-bar" in the rivet driving or heading operations.

The operation of the "dolly-bar" shown in Fig. 4 will be the same as for that shown in the other figures.

Modifications in the construction and arrangement of the part may be made without departing from my invention. The size and number of the plungers and co-acting springs may be increased; the manner of independently supporting the springs may be changed; and the means employed in holding the rivet snaps in position on the "dolly-bar" may be varied. The "dolly-bar" casing may be provided at an intermediate point in its length with a handle extending lengthwise transversely to the length of the casing, and other changes may be made without departing from the spirit of my invention as described and as covered by the appended claims.

I claim:

1. A dolly-bar comprising a hollow casing, said casing varying in internal diameter to form shoulders in different portions of the length thereof, a sectional plunger in said casing, a plurality of springs to hold the plunger at one end of its lengthwise travel, said springs engaging the shoulders in the casing, means connecting the casing to the plunger for limiting endwise movement of the plunger, and a rivet snap de- 130

- tachably secured in the end of one section of said plunger.
2. A dolly-bar comprising a hollow casing, a plunger lengthwise movable therein, said plunger having a plurality of shoulders thereon and having a rivet snap detachably secured on one end thereof, and yielding means for holding said plunger at one end of its lengthwise movement within the casing, said 10 yielding means comprising separate and independently operating springs, one end of said springs being in engagement with the casing, and the other end thereof engaging the shoulders on said plunger.
- 15 3. A dolly-bar comprising a hollow casing, a sectional plunger lengthwise movable in the casing, a rivet snap removably secured to the plunger, separate means for yieldingly holding each of said plunger sections at one end of the lengthwise travel
- 20

thereof, and means connecting the plunger and casing for limiting the lengthwise travel of the plunger in the casing.

4. A dolly-bar comprising a hollow casing, a plunger lengthwise movable therein and having a rivet snap detachably secured on one end, and yielding means for holding the plunger at one end of its lengthwise movement in the casing, said means including a plurality of separate and independently operating springs, one end of said springs connecting with the plunger, and the other end thereof engaging with the casing. 25
- 30

In testimony whereof, I have hereunto set 35
my hand.

HERBERT H. HUGHES.
